UNITED STATES PATENT OFFICE.

ISAC P. SIGGINS AND JAMES E. COOPER, OF PERRY, NEW YORK, ASSIGNEES TO ROBESON CUTLERY COMPANY, OF PERRY, NEW YORK, A CORPORATION OF NEW YORK.

KNIFE-HANDLE.

1,186,692.

Specification of Letters Patent. Patented June 13, 1916.

Application filed May 16, 1913. Serial No. 768,123.

To all whom it may concern:

Be it known that we, ISAC P. SIGGINS and JAMES E. COOPER, of Perry, in the county of Wyoming and State of New York, have invented certain new and useful Improvements in Knife-Handles; and I do hereby declare the following to be a full, clear, and exact description of the same, reference being had to the accompanying drawings, forming part of this specification and to the reference numerals marked thereon.

Our present invention relates to the manufacture of handles for knives and similar hand implements, and is more particularly adapted to the manufacture of handles for pocket knives and it has for its object to provide a slighty, strong and durable embossed handle that may be produced rapidly and cheaply in large numbers by a simple method and shaped, if desired, in imitation of the familiar stag or bone handles seen on the better grades of cutlery.

A further object of the invention is to provide a simple and efficient securing means for attaching the handle plate to the scale plate or corresponding part of the knife or implement which securing means is of a nature that lends itself to a method wherein the attaching together of the handle plate and scale plate may be accomplished simultaneously with the embossing operation performed on the handle plate.

To these and other ends the invention consists in certain improvements and combinations of parts all as will be hereinafter more fully described, the novel features being pointed out in the claim at the end of the specification.

In the drawings: Figure 1 is a top plan view of the female member of a die couple suitable for use in carrying out our invention and for producing pocket knife handles constructed in accordance with our invention; Fig. 2 is a longitudinal central section taken substantially on the line 2—2 of Fig. 1; Figs. 3 and 4 are transverse sections through the die couple taken substantially on the line 3—4 of Fig. 1, showing two steps in the operation of embossing one form of handle; Figs. 5 and 6 are similar views showing corresponding steps, respectively, in the operation of embossing another form of handle; Fig. 7 is a plan view of a scale

plate for a handle of the form shown in process of formation in Figs. 3 and 4; Fig. 8 is a plan view of the handle blank for the same handle; Fig. 9 is a cross section on the line 9—9 of the scale plate of Fig. 7; Fig. 10 is a cross section on the line 10—10 of the handle blank shown in Fig. 8; Fig. 11 is a cross section of the scale plate and blank assembled ready for embossing and for attachment to each other; Fig. 12 is a similar view in section through the finished handle, and Fig. 13 is a plan view of another form of scale plate for the construction of a handle such as that shown in process of formation in Figs. 5 and 6.

Similar reference numerals throughout the several figures indicate the same parts.

Aside from the cost of the material itself, one of the chief objections, from a manufacturing standpoint, to the use of bone, horn and other similarly frangible substances as handle plates for pocket knives and similar implements is that there is a considerable percentage of loss and waste due to the cracking or chipping of the handle plate both in the course of manufacture and subsequently when the knife is in use. In the factory, the application of the rivets commonly used to hold the knife together and to secure the handle plates thereon is perhaps the most frequent cause of this chipping and breaking, whereas the handle plate of the finished knife will often crack from simply being dropped upon a hard surface. By the practice of our invention, on the other hand, handle plates in exact imitation of the less serviceable and relatively expensive materials mentioned may be made from paper and emerge in the finished article as a practically indestructible, handsome and more securely fastened element of the knife structure.

In the present embodiment of the invention, we illustrate and will conduct our description with respect to the making of handles for pocket knives, but the invention has a more general application, as before indicated.

To the ends above pointed out, we prefer to construct the scale plate of the knife, to which the handle plate is directly connected and between a pair of which the springs, blades and linings are comprised, in the

manner illustrated more particularly in Figs. 7 and 9 wherein 1 indicates the plate proper, 2 the bolsters and 3 shallow flanges turned outwardly substantially at right angles on the lateral edges of the plate between the bolsters. Within the space delimitated by the said bolsters and flanges, we superpose a handle blank 4 conforming substantially to the said space in general outline as shown, but preferably thick enough to extend slightly above the flanges 3, as shown in Fig. 11. This blank 4 is preferably composed of hard, black paper or what is known as "commercial fiber", the substance of this nature largely used in electrical apparatus as an insulating material being eminently suitable.

The two parts thus assembled are then laid within the cavity of a female die block 20 5 with the scale plate 1 uppermost and the blank 4 beneath. The bottom of the cavity with the exceptions of the end portions 6 which receive the bolsters 2 and hence may be plain is wrought or fashioned as shown 25 at 7 in the manner of an embossing die to constitute the complement of the design that it is wished to produce upon the handle, which design, in the present instance, simulates the carved appearance of bone or stag 30 30 as used on knife handles. At this point, the blank 4 lies well above the surface 7, as shown in Fig. 8, its corners resting on the sides of the cavity which are inclined or tapered to converge toward the bottom as indicated at 8 for a purpose that will presently appear.

The male die 9 is then brought down and the plate 1 and blank 4 driven down together flatwise to the bottom of the cavity, 40 as shown in Fig. 4, and compressed between the die members under extreme pressure, say in the neighborhood of twenty tons to the square inch, or sufficient to embed the design 7 upon the under face of the blank 4. Simultaneously with this action, the flanges 3 of the scale plate 1 are forced inwardly from the side by reason of the tapered walls 8 of the die cavity and embedded in the edges of the blank 4 which is compressed edgewise 45 50 between them, as shown in Fig. 12. At the same time, the upper portions of the edges of the blank, as shown at 10 in Fig. 12, are locally compressed laterally in a direction transverse to that of the embossing pressure 55 60 by reason of a similar and more direct action of the inclines 8 and the material in that region is caused to, in a measure, flow about the flange 3 in each instance and form an absolutely tight joint therewith. It may be 65 70 said at this point that in order to increase the ductility of the fibrous material the blanks 4 are preferably heated just prior to their introduction between the dies and pressed out while hot or, if desired, the dies 75 80 themselves may be heated.

Were it not for the lateral or edgewise compression of the blank 4 as performed by the tapered walls 8 of the die cavities simultaneously with the embossing of the flat face thereof, the superiority of the finished article, particularly in the matter of its integrity of structure, would be greatly impaired if not destroyed and this for the reason that fibrous material of the nature contemplated for use in the practice of this invention usually possesses a more or less distinct "grain" and a stratified or laminated texture, as a result of which extreme pressure in one direction only has a disposition to disrupt the cohesion of its fibers, particularly at the exposed edges or surfaces. This characteristic has a parallel in and may be understood from the appearance of the edges of heavy cardboard or even those of thick hot pressed paper which may be readily split with the finger nail though the plane faces of the sheet are hard and resist the same attack. With the method described, however, the wedging action of the walls 8 of the die combined with the direct pressure of the male die makes the actual compression of the blank more pronounced and extreme in the region of the edges and the attenuated portions indicated at 10 in Fig. 12 as well as the corner that fits in the angle formed by the flange 3 and the body of the scale plate 1 are made practically impervious. It is also evident that the securing flanges of the plate 1 are embedded so intimately into the material of the blank that the parts are secured together beyond any reasonable possibility of separation.

While we prefer to fasten an embossed handle plate upon the scale plate in the manner described and in conjunction with the embossing operation, it is apparent that the handle plate may be embossed alone and subsequently applied to the scale in any desired manner. We have indicated the operations on the blank alone in Figs. 5 and 6, however, the only practical difference being that the blank 4 is placed in the cavity of the female die alone as shown and the entire lateral edge thereof, in each instance, comes in contact with and conforms itself to the tapered wall 8 which brings it to a sharp edge compressed by the pressure in two directions as above pointed out, to a self-sustaining hardness. When removed from the die, it is trimmed to a proper length to fit 105 between the bolsters 2 and then riveted in place on the scale 1^a, as shown at the points 2^a in Fig. 13 which is the ordinary manner 110 of fastening a handle plate in place. Of course, the handle plate in either instance 115 is trimmed off and buffed up in the usual manner and it may be said in this connection that so hard is the finished article that it responds to buffing and polishing with a high 120 gloss equal to that of bone or stag or any 125 130

of the close grained materials and has none of the dead appearance usually characteristic of articles made from paper.

I claim as my invention:

5 As an article of manufacture, a handle of the character set forth, comprising a die-pressed embossed fiber handle plate and a flanged scale plate, the handle plate having lateral edges locally compressed in a direction

transverse to that of the embossing pressure to and the flanges of the scale plate being embedded against the said edges.
